UNITED STATES PATENT OFFICE.

AMEL F. BAHR AND OTTO B. BAHR, OF MARION, INDIANA.

SHELL-LINING FOR PAPER-PULP-GRINDING MILLS.

1,133,215.

Specification of Letters Patent. Patented Mar. 23, 1915.

Application filed August 5, 1913. Serial No. 733,218.

To all whom it may concern:

Be it known that we, AMEL F. BAHR and OTTO B. BAHR, citizens of the United States, residing at Marion, in the county of Grant 5 and State of Indiana, have invented certain new and useful Improvements in Shell-Linings for Paper-Pulp-Grinding Mills, of which the following is a specification.

The present invention relates to improvements in paper pulp grinding mills, and has particular reference to the shell-linings for these mills, the object in view being to provide linings which comprise one or more longitudinal sections, each of these sections 15 having its inner surface formed with peculiarly arranged blades or ribs. While it has been proposed heretofore to provide various arrangements of the internal ribs in shell linings by means of which the pulp 20 is more or less retarded in its flow through the mill, our particular arrangement is designed not only to prevent too rapid passage but to promote the disintegrating action of the pulp and to this end blades are formed 25 in series, the staggered arrangement of one series being cast at an angle to the arrangement of its adjacent series.

With the above and other objects in view, this invention consists in the construction, 30 combination and arrangement of parts all as hereinafter more fully described, claimed and illustrated in the accompanying drawings, wherein—

Figure 1 is a longitudinal section of a 35 mill showing the application of our special form of shell-lining. Fig. 2 is an elevation of the lining alone. Fig. 3 is a vertical sectional view on the line 3—3 of Fig. 1 and showing a portion of the outer casing to 40 which the lining is secured. Fig. 4 is a plan view of the inner surface of one of the longitudinal sections of which the shell-lining is composed.

Throughout the following detail description, and on the several figures of the drawings, similar parts are referred to by like reference characters.

Referring to the drawings and particularly describing the mill to which our invention is applied, the outer casing 1 is formed like a hollow truncated cone and is preferably constructed of metal or of wood suited for this purpose with its larger end open and its smaller end closed by the integral cover 2. The larger open end portion of the casing 1 is provided with a re-

movable cover 3 which is fitted to the face of the flange portion 4 to form a close joint, being secured by means of bolts 5. Revolvably mounted within the mill casing 1, on the shaft 6 is a center or plug 7 keyed upon the shaft 6 and provided on its periphery with staves 8. This plug has a true conical surface and as is usual the surface is provided with a plurality of longitudinal knives 65 9 disposed between the staves 8 as shown most clearly in Fig. 1 of the drawings, these knives coöperating with the knives or blades formed on the shell-lining 10 which is secured to the inner portion of the casing 1 70 by means of bolts or similar fastenings 11.

Our invention resides primarily in the construction of the shell-lining as will now be described.

Since the casings 1 of mills are often constructed of wood or even when of metal, the constant use causes a certain amount of wear so that the renewing of the shell-lining becomes a difficult matter when it is considered that most of these linings are composed of hollow truncated cone sections. Furthermore, in certain makes of the casings are provided anchor bars arranged longitudinally at intervals around the inside circumference and these project above the 85 interior surface of the shell, making it impractical to properly fit the circular cone sections of which the lining may be composed. For this reason we have constructed our shell-lining in one or more longitudinal 90 sections as shown most clearly in Figs. 2, 3 and 4, the illustration of complete lining comprising four such sections. It would be obvious that by reason of the use of the longitudinal sections, linings can be very 95 easily placed between the anchor bars 12 which project inwardly from the interior casing 1 and when tightly positioned the several sections may be secured in position by the bolts 11, which pass through openings 11' in the lining sections. Each of these longitudinal sections is provided with a peculiar arrangement of blades or ribs designed particularly to properly disintegrate the paper pulp in its coöperation with the revoluble plug 8, the passage of the pulp through the mill being properly retarded so that the mastication may be very thorough.

To this end the blades 13 are arranged in one or more series, the several series on each 110 section of the lining 10 being designated in Fig. 4 by the letters *a, b, c, d* and *e*, the num-

ber of these series being arbitrary and governed according to the character of the pulp with which the machine is used. Furthermore, each of the series above referred to 5 consists of opposing annular rows of blades, $a', a'', b', b'', c', c''$, et cetera, that is to say, the blades of one row are staggered in relation to the blades of its adjacent row, the blades of both rows being parallel and 10 diagonally formed upon the interior surface of the shell section. This staggered arrangement forces the pulp to pass from one row to the next row over the ends of the blades and is, therefore, thoroughly ground between the lining and the cooperating plug 8. 15 In addition to the foregoing, the blades of alternating series are disposed at angles to the blades of its adjacent series, the result of this formation being to cause the pulp 20 in passing through the machine to take a serpentine path and thereby retard its flow so that it will be properly masticated when it issues from its grinding process. This particular arrangement of blades provides 25 the retarding action as above described which is usually accomplished by the provision of lugs in various forms of shell-linings but the use of these lugs is accompanied by numerous disadvantages which 30 are overcome by our retarding arrangement.

Having thus described the invention, what is claimed as new is:

1. A lining shell for paper pulp grinding mills comprising a hollow body and means

thereon for imparting to the pulp a tortuous movement, comprising a series of spaced annularly arranged blades, other blades disposed to close the spaces between said first mentioned blades whereby to impart to the pulp an in and out movement with respect to the longitudinal axis of the lining, and still other blades arranged at angles to the last mentioned blades whereby to impart to the pulp a tortuous movement circumferentially of the lining. 45

2. A lining shell for paper pulp grinding mills comprising a hollow body having internal longitudinal blades or ribs for imparting to the pulp a tortuous movement, said blades being spaced and arranged in a plurality of annular rows, the blades of one row being arranged to close the spaces between the blades of the adjacent row whereby to form an interrupted path to the flow of the pulp through said spaces, the blades 50 of the next row adjacent the last mentioned being arranged to close the spaces between the blades of said last mentioned row and also disposed at a position diagonal with respect thereto, and angularly with respect to the longitudinal axis of the lining.

In testimony whereof we affix our signatures in presence of two witnesses.

AMEL F. BAHR.
OTTO B. BAHR.
